(57) **CLAIM**

The ornamental design for a child toilet seat, as shown and described.

DESCRIPTION

FIG. 1 is a perspective view, as seen from the front left, of my design for a child toilet seat.

FIG. 2 is a top plan view of my design shown in FIG. 1.

FIG. 3 is a bottom plan view of my design shown in FIG. 1. FIG. 4 is a left side view of my design shown in FIG. 1, the right side being a mirror image thereof.

FIG. 5 is a front view of my design shown in FIG. 1.

FIG. 6 is a back view of my design shown in FIG. 1.

FIG. 7 is a perspective view, as seen from the bottom, of a child toilet seat of my design shown in a raised position.

FIG. 8 is a perspective view, as seen from the front left, of a child toilet seat of my design shown sitting on an adult toilet seat depicted in phantom.

FIG. 9 is a perspective view of a toilet seat of my design shown in a raised position in relation to an adult toilet seat depicted in phantom.

FIG. 10 is a top plan view of a child toilet seat of my design shown in a lowered position in relation to an adult toilet set and associated toilet depicted in phantom.

FIG. 11 is a perspective view, as seen from the bottom, of an alternative embodiment of my design for a child toilet seat; and,

FIG. 12 is a perspective view, as seen from the front left, of my design shown in FIG. 11.
